UNITED STATES PATENT OFFICE.

JOHN WEISBARTH, OF MADISON TOWNSHIP, RICHLAND COUNTY, OHIO, ASSIGNOR OF ONE-THIRD TO HENRY JOHN HOFFMAN AND ONE-THIRD TO CARL WILLIAM LAUBSCHER, OF MANSFIELD, OHIO.

WAX-HEATING AND SEALING DEVICE.

Application filed March 21, 1928. Serial No. 263,313.

This invention relates to a wax-heating and sealing device.

One of the objects of the present invention is to construct a device in one unit for the purpose of melting wax for sealing letters and packages containing money, jewelry valuable merchandise or the like.

A further object is to provide means for melting wax through the medium of an electrical heat unit which means has attached thereto auxiliary means for stamping an emblem, letters or the like in the wax material which has been melted by the electrical unit for the purpose intended.

15 A further object is to provide a means for holding and heating wax made in the form of a stick without changing the form or disassembling any part of the wax sealing device and which sealing stick of wax is constantly fed by gravity to the point where the same is discharged as it is melted preparatory to stamping and sealing the letter, package or the like.

Another object of the device consists in 25 providing a simple, durable and efficient unit device which is self-contained and can be operated with a minimum amount of time and labor to effectually seal and stamp the wax on letters, packages or the like without the assistance of any other tool or device in so doing and at the same time permit the operator to perform the work without mussing up or creating a disagreeable or dirty mess in so doing.

35 A further object is to provide a unit tubular member which is adapted to receive a handle, provided with means for holding or maintaining a stick of wax, means for mounting insulators thereon for mounting 40 the terminals of an electrical connection and also providing means for mounting thereon a heating element composed of resistance wire coiled around the tubular members in spaced apart relation.

45 Another object of the invention is to provide a device that can be manipulated to perform the functions desired for the purpose intended by one hand of the operator.

These and other objects are attained by the 50 mechanism illustrated in the accompanying drawing in which:—

Fig. 1 is a side elevation in vertical section of the invention showing the pivoted valve in closed position.

Fig. 2 is a vertical side elevation showing 55 the pivoted valve in closed position in full lines and in open position in dotted lines.

Fig. 3 shows a plan view of wax material having an emblem stamped therein.

In the drawing reference numeral 1 represents a tubular member which is preferably made of brass. The tubular member 1 is adapted to have mounted thereon the complete operating mechanism of the device. A wooden handle 2 is mounted upon one end 60 of the tubular member and is provided with a reduced portion 3 forming a collar.

A cup-shaped fibre member 4 is fitted to the reduced portion 3 and is adapted to house the terminals 5 and 6 of the wires 7 which supply 70 current from a light socket connection or other source of electric energy. Mica as indicated by reference numeral 8 is wrapped around the periphery of the tubular member 1 at its lower end and projects upward to a 75 point beyond the terminals of the wire 7 indicated at 9 for the purpose of insulation.

A resistance wire or the like 10 is connected to the terminal 5 and is coiled around the mica 8, each one of the coils being arranged in spaced apart relation from each other. The return end of the resistance wire 11 is attached to the terminal 6. The resistance wire 10 lies in close contact with the mica 8 insulating it from the tubular member 1 to 85 prevent short circuiting.

An insulating plastic compound 12 is pressed over and between the spaced apart coils of the resistance wire that is coiled around the tubular member 1, thereby insulating the coils of the resistance wire from each other and also forming a thin layer of insulating material over and around the resistance coils of wire.

A tubular jacket member 13 is provided and 90 is adapted to fit around the periphery of the insulating compound 12 to provide a smooth exterior finish for the lower portion of the tubular member 1. The upper portion of the tubular member is provided with an 100 outwardly extending flange 14 and a fibre washer 15 is attached thereto by beading or any other well known fastening means. The fibre washer 15 is attached to the handle 2 and the cup-shaped fibre member 4 by wood 105 screws or the like 16.

The washer 15 contacts with the bottom of the cup-shaped fibre member 4 forming a

chamber 17 to house the terminals 5 and 6. The lower end of the tubular jacket member 13 is turned inwardly forming an annular flange 18, the inner edge of which preferably contacts with the tubular member 1. The lower portion of the tubular member 1 is made or provided with a funnel-shaped member 19 having an outlet opening therein as indicated at 20.

10 The above describes the method of constructing the heating element of the device.

In the use of the device a stick of wax 21 or the like is inserted within the tubular member 1 and rests upon the curved shoulder portion 22 of the funnel member 19. Supply wires 7 are attached at their free ends to a plug 23 which is adapted to be attached to a light socket in the usual manner. The current is turned on or off by an ordinary switch, (not shown) and is adapted to pass through the coils of the resistance wire 10 which transmit heat to the tubular member 1; thence to the stick of wax, melting the same to permit it to flow and be discharged 25 from the outlet opening 20.

To prevent or permit the flow or discharge of the melted wax from the opening 20 as desired a valve mechanism is used which is constructed as follows:

30 An operating member 24 preferably formed U-shaped in cross section and preferably made of sheet material is provided with inwardly extending ear portions 25 which extend around and to the center of the cup-shaped fibre member 4 in opposed relation to each other and is pivoted thereon by pins or bolts 26. The operating member 24 is also provided with a handle portion 27 which is preferably made integral therewith. A 35 stamp 28 is provided for stamping an emblem, letters or the like into the wax after same is melted and deposited upon an envelope, pad or the like and is secured to the end of the operating member.

40 A valve comprising an arm 29 and a closure valve member 30 is provided and pivoted upon a pin 31. The valve is positioned on the operating member 24 so as to be adapted to close the outlet opening 20 when in normal 45 position. The end of the arm 29 is notched or bifurcated and is adapted to move in contact with the periphery of the jacket member 13 and tilted to close the outlet opening 20 when the operating member 24 is actuated 50 as shown in Fig. 2 in dotted and full lines.

The purpose of bifurcating or notching the upper end of the member 29 is to guide and keep the valve moving in true alignment with the outlet opening 20 of the tubular member 1.

55 The arm 29 is made heavier than the closure member 30 so as to permit it to overbalance the member 30 and thereby automatically keep the bifurcated or notched end 60 of the closure member 30 in contact with the

periphery of the jacket member 13 of the device, when in use. The valve closure member 30 is normally held in closed position, as shown in Fig. 2 by coil spring 32 which is compressed between the abuts against the handle 2 at one end and the opposite end abuts against the handle portion 27 of the operating member 24, thereby normally and under yielding tension exerting a pressure to maintain the closure member in closed position over the outlet opening 20 of the funnel-shaped member 19 as shown in full lines in Fig. 2.

When it is desired to permit the melted wax to flow from the opening 20, the handle 27 of the operating member 24 is pressed inwardly counteracting the tension of the spring and causing the operating member 24 to swing toward and to the dotted line position shown in Fig. 2 and away from the outlet opening 20, thereby permitting the melted wax to flow or be discharged from and through the outlet opening 20.

When the required amount of wax is discharged from the outlet opening 20, the pressure upon the handle 27 is released and the operating member and the valve closure member 30 carried thereby is forced by the pressure of the spring 32 to the position shown in full lines directly underneath and over the outlet opening 20 and in contact with the end of the funnel portion of the tubular member 1 as shown in Figs. 1 and 2, thereby preventing further flow of the wax from the outlet opening 20. This operation is repeated until the wax stick is exhausted, then if more sealing is required, other sticks of wax are inserted within the interior of the tubular member 1.

It will be noted that the operation of the device for sealing purposes can be carried on indefinitely without loss of time or labor by disassembling any part or portion of the wax sealing device to permit insertion of solid wax for melting.

The valve member is formed and the arm and closure members are spaced apart in such a relation to each other as to provide for the closure member being moved in close contact with the end of the funnel-shaped portion of the tubular member, so as to close the outlet opening 20 therein and at the same time provide for the bifurcated end of the arm 29 being moved in contact with the periphery of the jacket member 13 during the use of the device.

The operation in brief as follows:

The socket member 23 is connected to a conventional light socket which is controlled by the ordinary snap switch. When the current is turned on it is conducted to the coiled resistance wire 10 heating the element which transmits its heat to the stick of wax 21 melting same.

When the stick of wax is reduced by the

process of heating to a liquid state, the operator grasps the handle 2 and then presses the fingers on the handle 27 pivoting the operating member 24 from its normal position as shown in Fig. 2, which operation withdraws the closure member from its position over the outlet opening 20, thereby allowing the wax to be discharged or flow from said opening.

- 10 When the desired amount of wax for sealing has been discharged from the outlet opening 20, the handle 27 is released and the operating member which carries the valve mechanism is automatically moved by the compressed spring 32 to its normal or closed position and the flow or discharge of the melted wax is thereby cut off by the closure member 30. The stamp 28 carried by the operating member 24 is then pressed into the wax material forming therein any emblem, letter or 20 the like that is formed on the stamp.

It will be noted that the device for all purposes intended can be manipulated or operated by one hand of the user.

25 I claim:

1. In a wax melting and sealing device, a member adapted to receive wax or the like, an electric heating element associated with the first mentioned member and adapted to be connected to an electric circuit, means for carrying a stamp which is pivotally attached to the wax receiving member, and an independent separate valve mechanism pivotally attached to the stamp carrying means in spaced relation to the stamp which is actuated by the stamp carrying means.

2. In a wax melting and sealing device, a member adapted to receive wax or the like, an electric heating element associated with the first mentioned member and adapted to be connected to an electric circuit, means for carrying a stamp which is pivotally attached to the wax receiving member, and an independent separate valve mechanism pivotally attached to the stamp carrying means in spaced relation to the stamp which is actuated by the stamp carrying means, the stamp being supported in spaced relation to the wax receiving member.

3. In a combined wax melting and sealing device, a unit tubular member comprising a container which is adapted to receive and support a stick of wax preparatory to melting same, said tubular member being provided with a funnel-shaped portion having a restricted opening in the lower end, means secured to the tubular member to provide a chamber for the terminals of the wires of an electric circuit, a member attached to the exterior of the means providing the chamber which carries a stamp which extends below the restricted opening of the tubular member, an independent separate valve mechanism located in close proximity to the restricted opening of the unit tubular member and adapted

to be operated by the means carrying the stamp to close or open the restricted opening of the unit tubular member and located in separate relation from the stamp, as and for the purpose described.

4. In a combined wax melting and sealing device, a unit tubular member comprising a container which is adapted to receive a stick of wax, a cup-shaped member and a washer mounted on the tubular member to provide a chamber for the terminals of an electric wire, a resistance wire connected to an electric circuit coiled around the lower portion of the unit tubular member, a member pivoted to the parts forming the chamber carrying a stamp at its lower end and which is positioned in spaced relation to the lower end of the unit tubular member, an independent separate valve mechanism pivotally mounted on the member carrying the stamp and located in separate relation from the stamp which is adapted to close the opening in the lower portion of the tubular member and open same at the will of the operator.

5. In a combined wax melting and sealing device, a unit tubular member having a resistance wire coiled around a portion thereof, an insulated handle mounted on the tubular member, means to provide a chamber for the terminals of an electric circuit and which is attached to the insulated handle and mounted on the exterior of the tubular member, means pivotally attached to the means providing the chamber having a stamp attached thereto which is positioned in spaced relation to the lower portion of the tubular member, an independent separate valve mechanism pivotally attached to the stamp and in spaced apart relation from the stamp carrying means which is adapted to close or open the aperture formed in the lower end of the tubular member when actuated.

6. In a combined wax melting and sealing device, a unit tubular member open at the top, a wooden handle provided with a reduced portion and mounted on the unit tubular member, a cup-shaped fibre member mounted on the reduced portion of the handle, a fibre washer mounted on the tubular member and arranged to contact with the cup-shaped fibre member providing a chamber, a funnel-shaped portion provided on the lower portion of the unit tubular member and provided with an outlet opening, a resistance wire coiled around the unit tubular member and connected to a source of electrical energy, terminals and the ends of a resistance wire mounted in the chamber formed by the cup-shaped member and fibre washer, and means to permit or prevent as desired the discharge of the melted wax from the outlet opening provided in the funnel-shaped portion of the unit tubular member.

7. In a combined wax melting and sealing device, a unit tubular member having the

top thereof open and a restricted opening in the lower portion to provide means for inserting and supporting a stick of wax therein, a wooden handle mounted on the upper portion of the unit tubular member, a resistance wire coiled around the lower portion of the unit tubular member and connected to an electric circuit, a cup-shaped fibre member and a fibre washer mounted on the unit tubular member providing a chamber for the terminals of the resistance wire, an operating member pivotally attached to the cup-shaped fibre member, a valve mechanism comprising a closure member and an arm pivotally mounted on the operating member and adapted to be actuated to open or close the restricted outlet opening at the will of the user.

8. In a device of the character described, a tubular member adapted for insertion at one end of a stick of wax, a resistance wire coiled around the tubular member and adapted to be connected to an electric circuit, a handle made of wood mounted on the upper portion of the tubular member and having an enlarged portion at the bottom thereof, a cup-shaped fibre member attached to the enlarged portion of the handle and a fibre washer attached to the cup-shaped member to form a chamber around the exterior of the tubular member to house the terminals of the electrical circuit in association with the cup-shaped member.

9. In a device of the character described, a tubular member adapted for insertion of a stick of wax, a resistance wire coiled around the tubular member and adapted to be connected to an electric circuit, a handle made of wood mounted on the upper portion of the tubular member and having an enlarged lower portion, a cup-shaped fibre member mounted on the handle and attached to the lower portion of the wooden handle, a fibre washer attached to the cup-shaped member forming a chamber in association with the cup-shaped member, an independent means pivotally connected to the cup-shaped fibre

member and having its lower portion positioned in spaced relation from the bottom of the tubular member and also having a stamp secured thereto.

10. In a device of the character described, a tubular member adapted for insertion of a stick of wax, a resistance wire coiled around the tubular member and adapted to be connected to an electric circuit, a handle made of wood mounted on the upper portion of the tubular member and having an enlarged lower portion, a cup-shaped fibre member mounted on the handle and attached to the lower portion of the wooden handle, a fibre washer attached to the cup-shaped member forming a chamber in association with the cup-shaped member, means pivotally connected to the cup-shaped fibre member and having its lower portion positioned in spaced relation from the bottom of the tubular member and also having a stamp secured thereto, an independent valve mechanism pivotally attached to the operating means and adapted to close or open the aperture provided in the lower portion of the tubular member to permit or prevent the flow of wax as desired.

11. In a combined wax melting and sealing device, a unit tubular member, a handle made of wood attached to the upper portion thereof, a heating device comprising a resistance wire coiled around the lower portion of the unit tubular member, fibre members attached to the wooden handle thereof to house terminals of an electric circuit, means secured to the housing that carries a stamp on the lower end thereof, which stamp is positioned in spaced relation to the aperture formed in the unit tubular member, an independent valve mechanism pivotally attached to the stamp carrying means which is adapted to close or open the aperture formed in the tubular member when the means carrying the stamp is actuated.

In testimony whereof I affix my signature.

JOHN WEISBARTH.
